THROTTLE VALVE HAVING FLOW PASSAGES FOR MINIMIZING DRIFT

T Cyril Noon, Bainbridge Township, Geauga County, and Walter R. Chapman, Bedford, Ohio, assignors to Thompson Ramo Wooldridge Inc., a corporation of Ohio

Original application April 27, 1949, Serial No. 89,884, now Patent No. 2,707,866, dated May 10, 1955. Divided and this application April 24, 1953, Serial No. 350,996

2 Claims. (Cl. 251—63)

The subject matter of this disclosure constitutes a division of our copending application Serial No. 89,884, filed April 27, 1949, issued as United States Patent No. 2,707,866.

The present invention relates generally to a fuel control unit to be used in conjunction with an electronic fluid control circuit of the type disclosed in the copending applications of Offner Serial Nos. 13,546, now United States Patent 2,573,596, and 770,872.

This disclosure emphasizes features of the throttle valve incorporated in the fuel control unit.

An object of the present invention is to provide an improved balanced throttle valve wherein flow through the valve is controlled by positioning a balanced floating piston.

Many other features, advantages and additional objects of the present invention will become manifest to those versed in the art upon making reference to the detailed description which follows and the accompanying sheets of drawings in which a preferred structural embodiment incorporating the principles of the present invention are shown by way of illustrative example.

Figure 1 is a view in elevation, partly in section, of the throttle unit;

Figure 2 is a view in elevation partly in section of the throttle unit of the invention.

For an understanding of the environment in which the throttle valve 19 of the invention may be utilized reference is made to applicants' parent Patent No. 2,707,866, issued May 10, 1955. The throttle valve 19 comprises a valve body having a cylindrical bore closed by end plates 117, and is provided with a port 39 communicating with the upper end of the throttle valve and a port 43 communicating with the lower end thereof as hereinafter described.

The function of the throttle valve 19 is to meter flow to a nozzle or the like. It is composed of a free-floating hydraulically balanced piston 105 having upper and lower lands 113 and 116 respectively controlling orifices 106 and 107 formed in a throttle valve sleeve 108. In Figure 1, the fuel flows into an annular passage 110 suitably connected to a source of fluid under pressure (not shown). From the annular passage 110 in the throttle valve body, the fuel flows through the metering port 106 into sleeve 108 and out through port 107 and thence out the outlet 112.

Referring to Figure 1, the upper piston land 113 is provided with a groove 114 and a leakage path is formed by holes 115 to balance the pressure in the center zone between the upper piston land 113 and the lower piston land 116. In operation, the throttle valve is positioned by applying differential pressure into chambers 153 and 154. When the steady state condition exists, the differential pressure between the chambers 153 and 154 reduces to zero and it thus becomes important for the leakages across the upper and lower throttle valve piston lands to be equal. Unequal leakages across these lands change

2

the differential pressures in the chambers 153 and 154 and cause the piston to move without having any signal from the servo system.

Accordingly, the purpose and the advantages of groove 114 and holes 115 are to overcome such difficulties. The groove 114 is an annular groove around the periphery of the throttle valve piston. One side of the groove 114 connects with drilled holes 115 communicating with the center of the throttle valve piston. Thus, the combination achieved between the piston groove 114 and the drilled holes 115 is to provide the same leakage across each land of the throttle valve piston. By having equal leakages across the two lands of the throttle valve piston, minimum throttle valve piston drift is insured. The throttle housing 19 is provided with upper and lower closures 117 suitably affixed to the housing for assembling the piston 105 and the sleeve 108. Upper and lower adjusting stops 118 and 119 are provided for limiting piston 105 to a predetermined range of movement.

20 A starting solenoid 50 adapted to push out when energized, is mounted as illustrated in Figure 2, and provides a throttle stop during starting to prevent over-travel of the throttle valve piston. The solenoid 50 includes a winding 50a adapted to move a piston 50b outwardly 25 when energized by the line 52 from the electronic control.

An idle solenoid 51 is also provided and forms an idle fuel flow stop for the throttle valve piston during normal operation. In Figure 2, the idle solenoid 51 is shown normally biased outwardly in the path of movement of the throttle valve piston 105. The solenoid 51 thus includes spring means 51a for biasing the piston 51b outwardly as described, retraction being afforded by the winding 51c to include the line 53 from which the electronic control is connected.

30 Referring to Figure 2, the throttle valve 19 is provided with passages 120 and 121 connected to chambers formed above and below the upper piston land 122 and the lower piston land 116. These passages 120 and 121 are 35 connected to the ports 39 and 43.

In order to prevent a suction pull on the piston 105 by the local low static pressure which may be produced by increased velocity flow of fluid through the port 106, the piston is relieved as at 115a.

40 45 High pressure fuel or fluid is allowed to flow upward by the metering land and into the upper throttle valve chamber 153 through the passage 120 closing the throttle valve. Fuel in the lower throttle chamber 154 is vented to the lower pressure port 148.

50 55 While we have resorted to detail in the description of our invention for the sake of clarity, it will, of course, be understood that many modifications with respect to various details will suggest themselves to those versed in the art which will not mark a departure from the true spirit of our invention. We desire to incorporate within the scope of the patent warranted hereon all such modifications as reasonably and properly come within the scope of our contribution to the art.

We claim as our invention:

60 1. A throttle valve comprising a sleeve having an inlet port and an outlet port, a piston valve slidable in said sleeve to control the flow of fluid through said ports and including a first land and a second land spaced longitudinally therefrom, said lands being of different 65 longitudinal dimension wherein the longer of said lands will completely overlie one of said ports in one position of said piston, and passage means including an annular peripheral groove in said longer of said lands and interconnecting said inlet and outlet ports whenever said piston is in said one position, thereby to insure a flow 70 passage between said ports and balancing pressure differentials therebetween.

2. A throttle valve comprising a sleeve having an inlet port and an outlet port, a piston valve slidable in said sleeve to control the flow of fluid through said ports and including a first land and a second land spaced longitudinally therefrom, said lands being of different longitudinal dimension wherein the longer of said lands will completely overlie one of said ports in one position of said piston, and passage means including an annular peripheral groove in said longer of said lands and interconnecting said inlet and outlet ports whenever said piston is in said one position, thereby to insure a flow passage between said ports and balancing pressure differentials therebetween, means on each of the opposite ends of said piston forming a motive surface in a pressure control chamber to hydraulically position said piston in said sleeve, a pair of longitudinally spaced openings in said sleeve at opposite ends of said piston, a first solenoid operated stop means including an adjustable projection extending through one of said spaced openings to prevent overtravel of the piston, and a second solenoid operated stop means including a second adjustable projection extending through the other of said openings in said sleeve to form a throttle stop at the other end of said piston.
